UNITED STATES PATENT OFFICE.

ALEXANDER DOM AND CHESLEY DOM, OF CINCINNATI, OHIO, ASSIGNEES TO THE
SAMUEL C. TATUM COMPANY, OF CINCINNATI, OHIO, A CORPORATION OF OHIO.

PAPER-PERFORATOR.

1,154,294.

Specification of Letters Patent. Patented Sept. 21, 1915.

Application filed June 7, 1915. Serial No. 32,527.

To all whom it may concern:

Be it known that we, ALEXANDER DOM and CHESLEY DOM, citizens of the United States, and residing at Cincinnati, in the county of 5 Hamilton and State of Ohio, have invented a new and useful Improvement in Paper-Perforators, of which the following specification is a full disclosure.

The invention relates to an improvement 10 in perforators and primarily to a hand-operated type for desk use in perforating sheets of paper. As disclosed, it provides a perforator, very simple in construction, with a few number of parts, conveniently assembled, and of increased durability over others in the commercial field for similar purposes. In the style represented, the punch supporting members are integral with their 15 supporting base for a definite punch spacing. Other styles for a selective punch spacing, having their punch containing heads adjustable, are comprehended and within the aspect of this invention, which is primarily directed to the devices for reciprocating the 20 punch members and in the punch or its shank construction.

An object, therefore, of the invention is to 25 provide a perforator with a rock shaft journaled in the punch supporting members having a groove longitudinally therein to meshingly receive a tooth formed within the circumference of the punch or its shank as a motion converting connection or transmitting connection between the parts, whereby 30 the punch is reciprocated upon rocking the shaft, and thereby forms a very strong lever connection, and also restricts the movement of the parts, without the use of auxiliary devices for connecting or confining 35 purposes.

Various other features and objects of the 40 invention will be more fully set forth in the description of the accompanying drawings, forming a part of this specification, and in such drawings like characters of reference 45 denote corresponding parts throughout the several views of which:—

Figure 1 is a top plan view of the perforator. Fig. 2 is a section on line 2—2, Fig. 1. 50 Fig. 3 is an end elevation. Fig. 4 is a perspective view of a punch member.

The perforator, as illustrated, provides a 55 base 1, and two punch supporting heads 2, 3, cast integral with the base 1, but such construction is only incident to a particular

style, it being obvious that the invention 60 herein is applicable in any form of head construction or its method of mounting. The heads and their base may also be made of sheet metal stampings instead of from cast 65 material. Each head has its lower portion elongated forwardly and slightly raised from the upper surface of the base, terminating with a slot 4, cut into the head as a 70 paper receiving throat beneath the punch members. The gage of the slot is usually of a degree within a safe capacity that the parts of the device will withstand. The throat divides the punch and die elements or 75 members of the perforator, the die herein being represented by an orifice 5 in the base, in registry with the movable punch member mounted in the head. The die, however, may be in the nature of an insert, removably secured in position and of various design of 80 perforating outline. The circular form herein illustrated is of the most common demand for this type of perforator. The shank 7 of the punch is milled to provide a tooth 9, extending transversely to the punch axis with 85 the clearance for the tooth flanks cut in arcs from the base of the tooth toward the periphery of the shank and each preferably of a radius approximately equal to that of the 90 rock shaft 10, which shaft journals in the heads normal to the punches. The shaft has a longitudinal groove 11 into which the tooth 9 meshes for reciprocating the punch with the rocking motion of the shaft. A single tooth engagement with the shaft in 95 the form shown enables the production of a large pitch of tooth and avoids shearing injury, as in cases wherein a plurality of fine pitch teeth are employed as rack and pinion. The coincidence of clearance arc and shaft 100 periphery provide stroke limits for the moving parts in either direction. Further, the clearance surface registers and engages with the periphery of the shaft under the wedge-like action to clampingly bind the shank 105 within its bearing, and also shoulders the upper portion of the shank upon the shaft relieving the tooth of excessive strains at the stroke limits. This is very advantageous and increases the life of the perforator and withstands the rough usage to which it is frequently subjected.

The single tooth connection presents quite an advantage in assembling the punches as 110 no error can be made as to the relative aline-

ment or plane of the punch ends. The groove 11 is extended the entire length of the shaft, and while not absolutely essential in the type of perforator illustrated, is of advantage in 5 assembling the parts, for the shaft can be slid in one direction through one head to another of the series. The shaft is provided with a handle 12 as a means for oscillating the same.

10 We claim:—

1. In a device of the class described, a base, bearings relatively spaced on said base, each provided with a throat slot, a shaft journaled in said bearings having a groove 15 longitudinally therein, a punch member for each bearing, each movably supported in its bearing to intercept the throat slot thereof and normal to said shaft having a tooth transversely formed within its circumference, meshing with said shaft groove and curved flank surfaces at opposite sides of the tooth each approximately of a radius equal to that of the shaft adapted to alternately shoulder upon said shaft confining 25 the punch movements.

2. In a device of the class described, a base, bearing members relatively spaced on said base each provided with a throat slot, a shaft journaled in said bearing members 30 having a groove longitudinally therein, a movable punch member within a bearing member having a tooth meshing with said shaft groove with an angular shaft shoulder- 35 ing tooth clearance surface adjacent a tooth flank for confining the punch movement and wedge-like clamping the punch between shaft and bearing.

3. In a device of the character described,

a punch having an upper notch and a lower notch in its side, the upper side of the 40 upper notch and the lower side of the lower notch being concave, but the other sides of the notches being so shaped that a single tooth is formed by the material of the punch left between the notches, a shaft having a 45 longitudinal slot and extending into the notches in the punch with the tooth received in the slot, and the concave sides of the notches being arcs of radius substantially 50 equal to that of the shaft, whereby they form upper and lower stops, respectively, against the shaft, for the punch when said punch is depressed or raised by rotation of the shaft with the tooth engaging in the slot, and means for operatively supporting said 55 punch and said shaft.

4. In a device of the class described, comprising a frame structure, a shaft journaled in said frame structure having a groove longitudinally therein, a punch member movable within said frame structure and normal to said shaft having a tooth transversely formed therein meshing with said shaft groove, and curved flanked surfaces at opposite sides of the tooth, each approximately 65 of a radius equal to that of the shaft, adapted to alternately shoulder upon said shaft confining the punch movements.

In witness whereof, we hereunto subscribe our names as attested by the two subscribing 70 witnesses.

ALEXANDER DOM.
CHESLEY DOM.
